BEN T. SAMS AND WALTER H. HOUT, OF WARRENSBURG, MISSOURI.

CURRENT-MOTOR.

1,164,403.

Specification of Letters Patent. Patented Dec. 14, 1915.

Application filed July 15, 1914. Serial No. 851,076.

To all whom it may concern:

Be it known that we, BEN T. SAMS and WALTER H. HOUT, citizens of the United States, and residents of Warrensburg, in the 5 county of Johnson and State of Missouri, have invented a new and Improved Current-Motor, of which the following is a full, clear, and exact description.

Our invention relates to current motors, 10 and has reference more particularly to a water wheel in the shape of a spiral formed by a cone surface and mounted to float in a water current at a suitable angle to the direction of the current with the cone surface 15 of the spiral. The current motor is further characterized by the provision in the spiral wheel thereof of means between the adjacent surfaces of the spiral for receiving the maximum energy from the current and 20 which means will prevent any back pressure during the operation of the wheel.

An object of the invention is to provide a simple, strong and efficient current motor of the spiral type which is adapted to support itself on the fluid by which it is actuated.

With the above and other objects in view, the nature of which will more fully appear as the description proceeds, the invention 30 consists in the novel construction, combination and arrangement of parts as herein fully described, illustrated and claimed.

In the accompanying drawings, forming part of the application, similar characters 35 of reference indicate corresponding parts in all the views, and Figure 1 is a perspective of a current motor embodying our invention; Fig. 2 is a perspective view of a fraction of the wheel showing in dotted lines the various positions of the paddles as the said 40 part of the spiral emerges from the water; Fig. 3 is a fragmentary perspective view of the spiral with the paddles therebetween showing in the dotted lines the different positions thereof as the spiral with the paddles enter the water; and Fig. 4 is a cross section showing the connection of the paddles with the spiral and the means limiting the 45 movement of the paddles in a predetermined direction.

Before proceeding to a more detailed description of our invention, it must be clearly understood that the provision of a cone- or funnel-shaped spiral without the paddles is in 55 itself a power-producing machine substan-

tially without any back pressure, and the addition of the foldable paddles to this spiral greatly increases the efficiency of the motor. The said foldable paddles can be used with any other shaped spirals and the efficiency of 60 said spirals will be increased, but the total efficiency of the motor will not be as large as when the said paddles are combined with a cone- or funnel-shaped spiral.

Referring to the drawings, 5 represents a 65 hollow shaft the ends of which are hermetically sealed and supported in suitable bearings carried by a suitable support. The ends of the shaft with its bearings and support are not shown, as they do not form 70 part of the invention. The voluminal displacement of the shaft 5 in water is such as to sustain the spiral and the paddles carried thereby at least half submerged in water. Wound spirally on the shaft 5 is a cone- 75 shaped surface 6 forming on the shaft a funnel-shaped spiral between the adjacent cone surfaces of which paddles 7 are provided. The said paddles 7 are preferably hinged to the concave surface of the spiral, while the 80 facing convex surface is provided with members 8 substantially parallel with the element of the cone surface and forming abutments for the corresponding non-hinged edge 85 of the paddles. Each member or abutment 8 prevents any further movement of the corresponding paddle past the plane passing through the axis of the spiral. The number 90 of paddles in each turn of the spiral will vary with the diameter of the spiral, also 95 the pitch of the spiral will vary in accordance therewith.

Although any angularity less than 90° between the concave surface of the cone-shaped spiral and the axis thereof will produce a good current motor, the maximum efficiency from the current is obtained by making the angularity between the axis of the spiral and the concave surface thereof equal substantially to 45°. The paddles *a*, *b*, *c*, *d* and *e* of the successive turns of the spiral are stepped relatively to each other so that when the paddle *e* has reached a point where it would begin to produce a back pressure in its further movement if it 100 were prevented from moving relatively to the spiral the paddle *a* is just entering the water, while the intermediate paddles, that is, *b*, *c* and *d*, are in a position such that the water is pushing directly against them and 105 110

maintaining said paddles against the members 8. The movement of the paddle *e* as the same emerges from the water, is illustrated in Fig. 2. The dotted lines *e'*, *e''*, *e'''* and *e''''* indicate the gradual displacement of said paddle *e*, as the same, after having done its work, reaches the point where the back pressure commences to equalize itself by the forward pressure produced by the 10 current; and due to the back pressure the paddle gives way and equalizes the said back pressure by slowly folding back against the concave surface of the spiral, and the said paddle moves upward and 15 edgewise out of the water, as illustrated by the consecutive dotted lines shown in Fig. 2. As soon as this part of the spiral wheel passes the vertical plane, after it emerges from water, the force of gravity will swing 20 the paddle against the abutment 8 before it enters the water level, the successive positions of paddle *e* being shown in Fig. 3 in dotted line and indicated in *e₁*, *e₂*, *e₃* and *e₄*. The stepped relation of the swinging or release paddles *a* to *e* inclusive is such as to 25 obtain a regular and steady movement of the motor, thereby obtaining a regular and steady power. The provision of the air-tight hollow shaft 5, making the motor self supporting, eliminates the necessity of a complicated mechanism for raising and lowering the motor due to the change of 30 water level. It may be remarked that any number of such motors may work side by side in a stream, the necessary arrangement 35 being made for collecting the power independently or collectively from said motors.

The current strikes the concave surface of the spiral at an angle shown by the arrow 40 in Fig. 1. The paddles between the concave and convex surfaces of the spiral form a dam or blockade for the direction of the current so that water must push through and by so doing turn the wheel or stop 45 flowing. The angle at which the current strikes the concave surface of the wheel may be varied, but preferably it should not strike the spiral surface at right angles to the axis of the spiral or parallelly thereto. 50 Therefore, the angle of variation is within 45° with the axis of the spiral.

From the foregoing description, taken in connection with the accompanying drawings, the advantage of the construction and 55 operation of the device shown will be readily understood by those skilled in the art to which the invention pertains, and while we have described the principle of operation, together with the device which we now 60 consider to be the best embodiment thereof, we desire to have it understood that the device shown is merely illustrative and that such changes may be made when desired as are within the scope of the appended claims.

65 Having thus described our invention, we

claim as new and desire to secure by Letters Patent:

1. In a current motor, a funnel-shaped spiral, paddles associated therewith and positioned within the turns of said spiral, said 70 paddles adapted to close with the normally operative flow of the fluid against the motor.

2. In a current motor, a funnel-shaped spiral and paddles hinged to the concave surface of said spiral within the turns thereof, said spiral having means limiting the movement of said paddles under the normally operative flow of the fluid against the motor. 75

3. In a current motor, a funnel-shaped 80 spiral, paddles hinged to the concave surface of said spiral within each turn thereof, and members extending on the convex surface of said spiral adapted to form abutments for said paddles when the same are 85 forced thereagainst under the normally operative flow of the fluid against the motor.

4. In a current motor, a funnel-shaped spiral, paddles hinged to the concave surface of said spiral within each turn thereof, said paddles being adapted to move on their hinges from the concave surface to the facing convex surface of the spiral, and members carried by the convex surface adapted to form an abutment for each paddle when the paddle is engaged by the normally operative flow of the fluid. 90 95

5. In a current motor, a floating shaft, a funnel-shaped spiral on the shaft rigid therewith, paddles hinged to the concave 100 surface of the spiral within the turns thereof, and means associated with the convex surface of the spiral and adapted to co-act with each of the paddles and to arrest the movement of the same under the operative 105 flow of the fluid.

6. In a current motor, a spiral and a plurality of paddles in each turn thereof, means connecting each paddle to the spiral and permitting the movement of the paddle from the concave surface of the spiral to the facing convex surface thereof, and means associated with the spiral preventing each paddle from moving beyond a plane passing through the axis of the spiral when said 115 paddle moves under the normal operative flow of the fluid. 110

7. In a current motor, a spiral and paddles carried thereby and mounted to move relative to said spirals so as to engage opposite spiral surfaces under the normal 120 operative flow of the fluid. 125

8. In a current motor, a spiral and paddles carried thereby, said paddles being hinged to said spiral at predetermined intervals so that opposite spiral surfaces are engaged by the paddles under the normal operative flow of the fluid. 125

9. In a current motor, a spiral, paddles carried thereby, means permitting the dis- 130

placement of said paddles relative to said spirals, and means associated with the spirals adapted to prevent the paddles from passing beyond the axis of the spiral when 5 moved relative to said spiral under the operative flow of the fluid.

10. In a current motor, a funnel-shaped spiral and paddles between the turns of said spiral adapted to engage the facing spiral surfaces under the operative flow of the fluid.

11. In a current motor, a hollow shaft having hermetically sealed ends, a funnel-shaped spiral on said shaft, paddles hinged 15 to the concave surfaces of the spiral, and

means associated with the convex surface of the spiral and adapted to co-act with the paddles whereby said paddles are prevented from moving on said hinges under the operative flow of the fluid beyond a plane passing through the axis of the spiral. 20

In testimony whereof we have signed our names to this specification in the presence of two subscribing witnesses.
